(57) **CLAIM**

The ornamental design for a laser marking device as shown and described.

DESCRIPTION

FIG. 1 is a left side view of a laser marking device;
FIG. 2 is a right side view of the laser marking device;
FIG. 3 is a front view of the laser marking device;
FIG. 4 is a rear view of the laser marking device;
FIG. 5 is a top view of the laser marking device;
FIG. 6 is a bottom view of the laser marking device;
FIG. 7 is a front perspective view of the laser marking device; and,
FIG. 8 is a rear perspective view of the laser marking device.
